UNITED STATES PATENT OFFICE

HENRY BERRY, OF HUNTINGTON, CONNECTICUT, ASSIGNOR TO THE DERBY SILVER COMPANY, OF SAME PLACE.

DESIGN FOR A BACK FOR BRUSHES.

SPECIFICATION forming part of Design No. 20,013, dated July 15, 1890.

Application filed June 16, 1890. Serial No. 355,657. Term of patent 7 years.

To all whom it may concern:

Be it known that I, HENRY BERRY, a citizen of the United States, residing in the township of Huntington, (Shelton,) and State of Connecticut, have invented and produced a new and original Design for a Back for Brushes and other Articles, of which the following is a specification, reference being had to the accompanying drawing, forming part thereof, and which shows a plan view of a back for brushes and other articles ornamented in accordance with my design.

The leading features of my design consist in the form or outline of the back and in the surface ornamentation thereon; and the leading elements of said surface ornamentation consist of an ornamental combined fanciful and foliate scroll-frame substantially conforming along its exterior edges with the outline of the back and inclosing a field upon which are displayed foliate and ornamental scrolls, all as shown in the drawing, and more particularly referred to hereinafter.

In the drawing, A designates the scroll-frame which incloses the field B of the back, upon which field are displayed the bed of sprays of leaves and flowers, the conventionalized foliate scroll C, the coiled scroll D, and incidental surface ornamentation, all as shown in the drawing.

When employing the design for a back of a brush and some other articles, the combined fanciful and foliate scroll-frame A, with the inclosed ornamental configurations, will alone be made use of; but where a more extended surface is required—such as for a mirror-back—the frame A will be surrounded by the field E, having an outline substantially conforming to that of the frame A and bearing the conventionalized foliate scrolls F G, which closely unite with the sides and upper end of the frame A, as shown.

It will be noted that the frame A has a well-defined outline independent of the scrolls F G, but that when said scrolls F G are applied to the frame A the whole forms a concrete design of ornate character.

What I claim as my invention, and desire to secure by Letters Patent, is—

The design for a back for brushes, mirrors, and other articles, substantially as shown and described.

In witness whereof I hereunto affix my signature, at Shelton, Connecticut, this 13th day of June, 1890.

HENRY BERRY.

In presence of—

WESLEY L. CLARK,
M. A. WHITE.
